UNITED STATES PATENT OFFICE.

WILLIAM WALTER GERALD WEBB, OF LEAMINGTON, AND JOHN HALL,
OF ASHBY-DE-LA-ZOUCH, ENGLAND.

TARGET.

No. 799,697.

Specification of Letters Patent.

Patented Sept. 19, 1905.

Application filed January 18, 1905. Serial No. 241,678.

To all whom it may concern:

Be it known that we, WILLIAM WALTER GERALD WEBB, residing at Creeba, 6 Union road, Leamington, in the county of Warwick, 5 and JOHN HALL, residing at the Manor House, Overseal, Ashby-de-la-Zouch, in the county of Leicester, England, subjects of the King of Great Britain, have invented certain new and useful Improvements Relating to Targets, 10 of which the following is a specification.

This invention relates to targets for rifle and other ranges, and has for its object to provide for the automatic displayal and recording of the scores made by the marksman and 15 the frequency with which the target has been struck during any required interval of time.

The invention comprises the employment of a target constructed from independent sections or striking elements, each of which is 20 adapted to recede or recoil under the impact of a bullet, and the combination with the said target of electrically-actuated automatic signaling and recording apparatus arranged for operation with the recession or recoil of the 25 target-sections.

Referring to the six accompanying sheets of explanatory drawings, Figure 1 is a front elevation, and Fig. 2 a side elevation, of a target constructed in accordance with this invention, while Fig. 3 is a rear elevation of the 30 same. Fig. 4 is a front elevation of our automatic signaling and recording apparatus. Fig. 5 is a similar view with the cover-plate removed; and Fig. 6, a cross-section on the 35 line A B, Fig. 4. Fig. 7 illustrates to a larger scale than Figs. 5 and 6 one of the electrically-actuated signaling elements.

The same reference characters in the different views indicate the same or similar parts. 40 The target as shown by Figs. 1, 2, and 3 is constructed from a number of segments or striking elements *a*, mounted concentrically around a "bull's-eye" *b*. The outer segments may either be formed with a circular outline 45 or a rectangular outline, as shown at Fig. 1. Each segment *a*, including the bull's-eye *b*, is carried at a suitable distance in front of a pair of supporting-plates *c* and *d* by means of a plunger *e* and a pair of projecting guide- 50 pieces *f*, which pass through the front sup-

porting-plate *c*. The said guide-pieces *f* serve to maintain the segments in correct relation with each other. For the circular bull's-eye no guide-pieces are necessary. To return the segments to their original position after recession under the impact of a bullet, a spiral spring *g* is provided around a reduced rear portion of each plunger *e* and arranged to abut against the plate *d*. The plate *e* is carried at a suitable distance in front of the plate *d* by means of connecting-pieces *h*. The segments *a* are preferably so disposed, as shown at Fig. 2, that their front faces are not all in the same plane in order to prevent binding together of adjacent segments by bullets striking the division-lines between them. In conjunction with the rear extremity of each plunger is arranged an electric switch comprising a fixed contact-piece *i* and a movable spring-like contact-piece *j*. The said contact-piece *j* 7c is normally retained against its spring action out of contact with the piece *i* by means of an adjustable nut or collar *k* on the plunger *e*. After a segment has been struck and during its consequent recession the contact-piece *j* 75 of the corresponding switch is permitted to engage the piece *i*, and thereby complete a circuit through electric signaling and recording apparatus, as hereinafter described. With the said arrangement of the fixed and movable 8c contact-pieces a reliable and sensitive switch is obtained. A small movement of the corresponding target-segment under the influence of a slight impact suffices to close the switch, while a large movement under a heavy impact causes no damage thereto. Moreover, as by the said arrangement of contact-pieces the same remain in engagement during an appreciable interval of the time occupied by the recoil movements of the target-segments reliable operation of the recording mechanism is insured. Each switch is connected, by means of conducting-wires, to a pair of terminals, as *l*. When the segment resumes its original position, under the action of the spring *g* 95 around its plunger *e* the switch is simultaneously opened.

The signaling or displayal of the scores made by the marksman is automatically effected by electrically-actuated mechanism 100

connected with the target-segments. In each of the circuits passing through the target-switches is arranged an electromagnet *m*, Figs. 5, 6, and 7, adapted to release a catch, as *n*, 5 of a counterpoised disk *o*, bearing an appropriate number or other distinguishing device, and to so move or cause the said disk *o* to drop into position behind a sight-aperture in the front *p* of an inclosing casing *q*, where 10 the number or device can be readily seen. One electromagnet, as *m*, with a catch *n* and display-disk *o*, may be employed for each ring of segments, the separate segments being united to the same circuit; but preferably 15 an independent magnet, catch, and disk are employed for each segment, as illustrated. Each of the electromagnets is connected in any suitable manner to a pair of terminals, as *r*. The electromagnets can be actuated or 20 excited from batteries *s*, arranged compactly within the base of the inclosing casing. Any other source of electrical energy may, however, be utilized. The display-disks *o* are so 25 counterpoised that they remain in coincidence with their respective sight-apertures after the circuits through their magnets have been interrupted. For restoring the disks to their original or out-of-service position a number of trip-pieces *t* are provided upon a sliding 30 frame *u*, which is actuated by an external handle *v*. The said trip-pieces are arranged to engage lever-like projections *w* from the disks. By inwardly pressing the handle *v*, and thereby sliding the frame *u*, the disks *o* 35 are raised to their initial position, where they are retained by the aforesaid catches *n*.

For recording the number of times the target has been struck a dial *x*, having its face suitably divided, is employed in conjunction 40 with the display mechanism. The finger of the dial is connected to a gear or ratchet wheel *y*, which is intermittently rotated by a pawl *z*, operated by an electromagnet 1. All the segments *a* of the target may be arranged 45 or wired so that any one of them when struck by a bullet will complete the circuit through the said magnet 1, and thus excite the latter and cause it to advance the finger of the dial through one division; but the advance of the 50 dial-finger may also be obtained by means of a trip-piece 2, mounted on the aforesaid sliding frame *u* and adapted to operate the pawl *z*.

We also employ an electric gong 3 in connection with the target-segments for the purpose of giving audible signals when the target has been struck.

The display or signaling and recording mechanism aforesaid are mounted within the inclosing casing *q*, which may be situated in 55 any desired position upon the range. Connection between the target and the display and recording mechanism is effected by a cable containing the requisite number of wires

and provided at each extremity with plug-terminals 4, capable of being readily inserted 65 within the terminals *l* and *r*.

For the purpose of providing the marksman with a record or pattern of his shooting we arrange for the support of disks or tablets, as 5, of cardboard or other penetrable material in front of the target. The face of the disk is divided into rings corresponding with the rings of target-segments, so that the perforations formed by the bullets in the said disk afford accurate records or patterns of 75 his shooting. The card is carried by a pair of supports 6, sustained at the required position in front of the target by brackets or projecting members 7, secured to the framework 80 of the target. The position of the supports 80 6 can be adjusted by means of screws 8, capable of sliding within slots formed in the said members 7.

Having thus described our invention, what we claim as new, and desire to secure by Letters Patent, is—

1. In targets, the combination comprising a spring-controlled striking element adapted to recede or recoil under the impact of a bullet, a plunger united with the said striking element, an electric switch held open by the plunger when the latter is at rest and automatically closed during the recoil movements of the plunger, and electrical signaling apparatus having its circuit completed by the said 95 switch, substantially as set forth.

2. In targets, the combination comprising a striking element adapted to recede or recoil under the impact of a bullet, a plunger united with the said striking element, supporting- 100 plates and an adjustable collar for the said plunger, a spring arranged with the plunger, an electric switch maintained in the open position by the said adjustable collar when the plunger is at rest and automatically closed 105 during the recoil movements of the plunger, and an electrical signaling device having its circuit completed by the said switch, substantially as described.

3. In targets, the combination comprising 110 spring-controlled striking elements adapted to recede or recoil under the impact of bullets, plungers united with the said elements electric switches held open by the plungers when the latter are at rest and automatically 115 closed during the recoil movements of the plungers, electrical signaling apparatus having its circuits completed by the said switches, and means for recording the number of target-hits, substantially as described.

4. In targets, the combination comprising 120 spring-controlled striking elements adapted to recede or recoil under the impact of bullets, plungers united with the said elements, electric switches held open by the plungers 125 and automatically closed during the recoil

movements of the plungers, automatic signaling apparatus arranged in electrical connection with the said striking elements, a disk or tablet of penetrable material arranged in front of the striking elements, and adjustable supports for the said disk, or tablet, substantially as set forth.

5 In testimony whereof we have signed our

names to this specification in the presence of two subscribing witnesses.
